DESIGN FOR A THERMOSTATICALLY CONTROLLED ELECTRIC WATER HEATER

Earl C. Gardner and Howard L. Cross,
Los Angeles, Calif.

Application April 23, 1941, Serial No. 100,580

Term of patent 14 years

To all whom it may concern:

Be it known that we, Earl C. Gardner and Howard L. Cross, citizens of the United States of America and residents of Los Angeles, in the county of Los Angeles, State of California, have invented a new, original, and ornamental Design for a Thermostatically Controlled Electric Water Heater, of which the following is a specification, reference being had to the accompanying drawing, forming a part thereof.

In the drawing:

Figure 1 is a side elevational view of a thermo-

statically controlled electric water heater showing our new design.

Figure 2 is an end elevational view of the handle end of the encasing portion shown in Figure 1; and,

Figure 3 is a similar view of the opposite end thereof.

We claim:

The ornamental design for a thermostatically controlled electric water heater, as shown.

EARL C. GARDNER.
HOWARD L. CROSS.
